CLAIM

The ornamental design for a junction box, as shown and described.

DESCRIPTION

FIG. 1 is a front perspective view of a junction box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

(Continued)

FIG. 9 is front perspective view of the junction box, shown in an open state.

The broken lines in the drawings illustrate the portions of the junction box, which form no part of the claimed design.

1 Claim, 9 Drawing Sheets
